UNITED STATES PATENT OFFICE.

ARCHIE COUCHMAN, LOUIS F. DRINKHAHN, AND WALTER L. PHILLIPS, OF DETROIT,
MICHIGAN.

LUBRICATING SYSTEM.

Application filed March 22, 1926. Serial No. 96,369.

This invention relates to improvements in lubricating systems and refers more particularly to lubricating systems for locomotive driving boxes and side rod brasses.

5 Broadly speaking this invention aims to provide a lubricating system wherein positive means are employed for continuously forcing a lubricant in small quantities into the driving boxes and side rod brasses as 10 long as the locomotive on which the system is arranged travels in either direction.

A preferred embodiment of the invention is hereinafter more fully described with the aid of the accompanying drawings, in which:

15 Figure 1 illustrates a plan view of the invention.

Figure 2 is a section on the line 2—2 of Figure 1.

Figure 3 is a general plan view showing 20 the application of one lubricator for all the driving boxes and side rod brasses.

Figure 4 is a section on the line 4—4 of Figure 1.

Figure 5 is a fragmentary view showing 25 the underside of a reservoir and portion of a transverse locking plate.

Figure 6 is a section on the line 6—6 of Figure 1.

Figure 7 is a section on the line 7—7 of 30 Figure 1, and

Figure 8 shows a plan view of the cam.

Figure 9 shows a modification wherein the cam is integral with one of the reservoir collars.

35 Referring now to the drawings, 1 designates ordinary locomotive frames having the usual axle boxes 2 mounted therein and driving axles 3 journaled in the boxes. Between the frames and usually supported 40 thereby is a platform 4 on which a lubricator 5 is secured. On one of the axles 3 a cam 6 is secured the periphery of which contacts a roller 7 revolvably mounted on the outer end of the rod 8 which is adapted to reciprocate in bearings 9 of the lubricator. The 45 spring 10 around the rod 8 holds the roller on the latter in engagement with the cam. A dog 11 pivotally mounted on the rod 8 engages the teeth of the ratchet wheel 12 which 50 is fixed on the shaft 13. On the latter is a sliding gear 14 which normally meshes with the gear 15. This gear 15 is provided with an internal thread which cooperates with the threaded portion 16 of the plunger rod. 55 This rod extends through the rear wall of

the container 18 and terminates in a plunger 19. 20 indicates discharge openings through the front of the container, and 21 is a filler connection usually closed as by a cap 21^a. The back end 22 of the plunger is preferably 60 smooth and is supported by a bearing 23 integral with the lubricator casing 24. The plunger rod terminates in a nut 25 having a collar 26 integral therewith. A shifter 27 is supported by the casing 24 and by a bearing 28 integral therewith, and is adapted to move longitudinally so that when the plunger has advanced to a predetermined position in the container the collar moves the shifter 27 inwards thereby rotating the 70 cut-out member 29 about its fulcrum point 30 and moving the sliding gear 14 out of engagement with the gear 15. After that occurs the continued rotation of the shaft 13 will not move the plunger. When the 75 container is to be reloaded the gear 15 must first be locked against rotation and then the plunger rod is turned with a wrench placed on the nut 25. This screws the threaded portion 16 of the plunger rod through the gear 80 15. After the plunger has been moved to the back of the container the latter is re-filled and the sliding gear 14, cut-out member 29, and shifter 27 returned to the position shown in Figure 1.

85 Around each driving axle 3 split collars 31 are firmly secured as by bolts 32. 33 indicates packing which is sometimes employed to insure tight joints around the axles. In the ways 34 split annular receivers 35 are slidably mounted so that the latter may remain stationary while the split collars 31 revolve with their axles 3. Integral with one of the sections of the reservoirs are projecting members 36 which pass 90 through apertures 37 in the locking plates 38, which latter extend transversely between, and are supported by, the frames. It will be noted that whereas this arrangement prevents the reservoirs from revolving lateral 95 and vertical movement of the projections 36 within the apertures 37 is permitted.

100 Through the reservoirs are holes 39 having flexible tubes 40 attached thereto, the opposite ends of which are connected to the discharge openings 20 of the container.

105 The axles 3 are hollow and have tightly plugged ends 41. 42 indicates passages from the interior of the reservoirs 35 into the bores of the axles. Onto the journals 43 ra-

dial openings 44 are provided from the bores of the axles, and other passages 45 also from the bores of the axles pass through the latter, through the wheels 46 and side rod pins 47 to the bearing surfaces of the latter. The side rod brasses are indicated at 48.

The operation of the system is as follows:

As the axles 3 rotate the cam 6 reciprocates the rod 8 thereby gradually advancing 10 the plunger 19 and forcing grease through the tubes 40 into the reservoirs 35. From the latter the lubricant passes through the hollow axles and, either through the openings 44 to the journals 43, or else through the passages 45 to the inside of the side rod brasses 48.

Obviously the cam 6 may, if desired, be made integral with one of the split collars 31 as shown at 31^a in Figure 9.

20 Moreover though one form of lubricator has been shown and described it is understood that any other lubricator so constructed that the lubricant will be continuously forced therefrom as the locomotive travels 25 may be substituted therefor. The lubricator must however be provided with automatic means for cutting out the forward travel of the plunger when the latter has reached a predetermined point.

30 The feed of the lubricator may if preferred be obtained from any other moving part of the locomotive, the movement however should be such that pressure will be exerted on the lubricant irrespective of the 35 direction of travel of the locomotive.

While in the foregoing the preferred embodiment of the invention has been described and shown, it is understood that the construction herein described is susceptible to 40 such modifications as fall within the scope of the appended claims.

What we claim as our invention and desire to secure by Letters Patent is:

1. In a lubricating system, the combination 45 with a locomotive having the usual frames, axle boxes mounted therein, and a hollow axle journalled in said boxes, of a lubricator mounted on said locomotive, a completely enclosed annular reservoir mounted around said hollow axle the ends of which latter are plugged, means for discharging lubricant from said lubricator as the locomotive travels, a discharge tube connecting said lubricator with said reservoir, said axle having a passage therethrough connecting its bore with the interior of said reservoir, and said axle also having other passages from its bore to the journals of said axle boxes.

2. In a lubricating system, the combination 60 with a locomotive having the usual frames, axle boxes mounted therein, a hollow axle journalled in said boxes, wheels on said axles, and side rod pins on said wheels, of a lubricator mounted on said locomotive, a completely enclosed annular res-

ervoir mounted around said hollow axle the ends of which latter are plugged, means for discharging lubricant from said lubricator as the engine travels, a discharge tube connecting said lubricator with said reservoir, 70 said axle having a passage connecting its bore with the interior of said reservoir, said axle also having other passages from its bore to the journals of said boxes, and the periphery of the side rod pins being connected by other passages with the bore of the axle, said latter passages passing through said axle, wheels, and side rod pins. 75

3. In a lubricating system, the combination with a locomotive having the usual 80 frames, axle boxes mounted therein, and hollow axles journalled in said boxes, of a lubricator mounted on said locomotive, means for discharging lubricant therefrom as the locomotive travels, collars secured around said 85 axle and adapted to rotate therewith, a reservoir supported between said collars, means for holding said reservoir stationary as said collars rotate, a discharge tube from said lubricator connected to said reservoir, said 90 axle having a radial passage from its bore opening into said reservoir and its hollow ends plugged, and the journals of said axle connected by passages with the bore thereof.

4. In a lubricating system, the combination 95 as described in claim 3, wherein the means for holding the reservoir stationary consists of a projection integral with said reservoir, and a locking plate supported between said frames having an opening therein 100 through which said projection passes.

5. In a lubricating system, the combination as described in claim 3, wherein the collars and the reservoir are split, and the former are provided with peripheral ways 105 around which the ends of the reservoir are adapted to slide.

6. In a lubricating system, the combination with a locomotive having the usual frames, axle boxes mounted therein, a hollow 110 axle journalled in said boxes, wheels on said axle, and side rod pins on said wheels, of split collars secured around said axle and adapted to revolve therewith, a completely 115 enclosed reservoir mounted between said collars forming an annular chamber around said axle, said collars forming part of the end walls of said reservoir, means for holding said reservoir against rotation, a lubricator mounted on said locomotive, means for 120 discharging lubricant from said lubricator, said axle having a passage therethrough connecting its bore with its periphery within said reservoir, said hollow axle having 125 plugged ends, the journals of said axle connected by passages with its bore, and the periphery of the side rod pins being connected with the bore of said axle by passages through said axle, wheels, and side rod pins.

7. In a lubricating system, the combina- 130

tion with a locomotive having the usual frames, axle boxes mounted therein, and hollow axles journalled in said boxes, of a lubricator mounted on said locomotive, a completely enclosed reservoir mounted around each of said hollow axles the ends of which latter are plugged, means for discharging lubricant from said lubricator as the locomotive travels, discharge tubes connecting said reservoirs with said lubricator, means for preventing said reservoirs rotating with said axles, said axles having passages therethrough connecting their bores with the interior of their reservoirs, and said axles also having other passages connecting their bores with the journals of said axle boxes.

8. In a lubricating system, the combination with a locomotive having the usual frames, axle boxes mounted therein, hollow axles journalled in said boxes, wheels on said axles, and side rod pins on said wheels, of a

lubricator mounted on said locomotive, collars around said axles adapted to rotate therewith, reservoirs supported between said collars, means for holding said reservoirs against rotation, discharge tubes from said lubricator to said reservoirs, means for discharging lubricant from said lubricator into said reservoirs as long as the locomotive travels in either direction, said axles having radial passages from their bores opening into said reservoirs and their hollow ends plugged, the journals of said axles connected by passages with the bore thereof, and the periphery of said side rod pins being connected by other passages with the bores of their axles, said passages passing through their axles, wheels, and side rod pins.
